UNITED STATES PATENT OFFICE.

PETER C. GREENAWALT, OF READING, PENNSYLVANIA, ASSIGNOR OF ONE-HALF TO WRIGHTSVILLE HARDWARE COMPANY, OF WRIGHTSVILLE, PENNSYLVANIA.

DETACHABLE HANDLE FOR SAD-IRONS.

SPECIFICATION forming part of Letters Patent No. 680,143, dated August 6, 1901.

Application filed February 28, 1901. Serial No. 49,262. (No model.)

To all whom it may concern:

Be it known that I, PETER C. GREENAWALT, a citizen of the United States, residing at Reading, in the county of Berks and State of Pennsylvania, have invented certain new and useful Improvements in Detachable Handles for Sad-Irons; and I do hereby declare the following to be a full, clear, and exact description of the invention, such as will enable others skilled in the art to which it appertains to make and use the same.

This invention relates to sad-irons having detachable handles; and the objects of the invention are to provide constructions, combinations, and arrangements of means whereby a detachable handle can be coupled to and uncoupled from the iron proper in a very ready and perfect manner; also, to provide a novel construction, combination, and arrangement with the iron proper and the handle-plate and handle proper of a spring-actuated latch whereby said handle can be automatically latched to the iron near both of its ends without manipulating the latch-button, it simply being required to take hold of the detachable handle and place it upon the iron proper in a position transverse to the said iron and then give the handle a quarter-turn, all as will be hereinafter described. These objects are accomplished by the devices described in the following specification, and illustrated in the accompanying drawings, in which latter—

Figure 1 represents a side elevation of the improved sad-iron, partly broken away to show the interior of the iron proper and parts which would be concealed otherwise. Fig. 2 represents a horizontal section of the improved iron looking upward. Fig. 3 represents a plan view of the iron with the handle removed. Fig. 4 represents an inverted plan view of the detachable handle. Fig. 5 is a detail cross-section of the handle, bottom connecting-plate, provided with a tubular inverted-T-shaped coupling-lug, and latch with lifting button or knob. Fig. 6 is a perspective view of the handle-plate, showing the lower side thereof; and Fig. 7 is a top plan view of the same.

A represents an iron proper; B, a handle proper; B', a metal plate connecting the base ends of the handle proper; b, a coupling-lug having lips b'; C, a spring-actuated latch; C', a knob or button by which the latch is raised to uncouple the handle from the iron proper; C², a spring for actuating the latch, and c a stud for centering and guiding the handle and also serving as a pivot for the handle to turn upon.

The body A of the iron is provided with a chamber a, and is provided with a removable cover or plate a', which is held in place by screws a² a², as clearly shown in Figs. 1 and 3. The plate a' is provided with an elongated passage a³, which is enlarged centrally of its length, as at a⁴, as clearly shown in Fig. 3. By this construction the top plate or cover a', adjacent to the passage a³, forms shoulders or flanges a⁵ for the engagement of the retaining-lips b' of the coupling-lug b to pass under after the lug has been inserted through the passage a³ and during the act of giving the handle a quarter-turn. The passage a³, enlarged, as at a⁴, allows of the introduction of the inverted-T-shaped coupling-lug while the handle is transverse to the iron, and the said flanges of the top plate serve for preventing the handle separating by an upward movement from the iron proper after the handle has been coupled in operative position to the iron.

The handle B is preferably made of wood and in curved form and has its base ends connected to the metal horizontal plate B' by means of screws E, having their heads countersunk into the said plate B', as shown. The plate B' is flat on its top and bottom and of oblong form and may have rounded edges and ends, the latter corresponding to the bottom ends of the handle proper. This plate is bulged on both sides between said handle ends, and in its bulged part vertical, segmental, or other suitably-shaped passages d' are provided, and between the passages d' a longitudinal slot d is provided for a purpose hereinafter described, and on the under side of the plate B' is cast a downwardly-projecting tubular lug b, having two horizontal lips

b' at its lower end. The lug, with its lips, forms an inverted-T-shaped coupling between the plate *B'* of the handle *B* and the iron proper, *A*. The lips *b'* are set down far enough 5 from the plate *B'* to leave spaces of a size about equal to or a very little greater than the thickness of the removable cover or top of the iron proper, and thus when the lips of the inverted-T-shaped coupling are fully inserted 10 into the chamber *a*, so as to bring said coupling-lips below this top plate, and the lug is turned by the handle so as to bring the same beneath the edges of the top plate, the said edges will occupy the space between the 15 lips and the handle-plate *B'* and prevent the handle from separating from the iron when an upward pull is exerted upon the handle or the iron lifted by the handle. The passage through the coupling-lug is flared down- 20 wardly.

The centering or guiding pivot or stud *c* is slightly conical and is cast on the iron proper, it rising from the bottom of the chamber *a* and extending up to near the top of the iron proper. This stud enters the central passage 25 of the tubular lug when the handle stands transversely of the iron and remains in said passage of the lug after the handle is adjusted to its working position, and thus the coupling-lug 30 of the handle-plate is centrally guided through the passage leading into the chamber *a*. When the handle has been properly adjusted, with the lug *b* between the inner edges of the top plate and its lips below the 35 same, the stud *c* serves as a pivot for it to turn upon, both in coupling it to and uncoupling it from the iron. The latch *C* consists of a long narrow body-bar with two broad vertical legs *c'*, one at each end. This latch is 40 fitted into the long vertical slot *d* in the plate *B'*, so as to extend across the coupling-lug *b* and nearly to the end of the plate. The slot 45 is open from top to bottom of the plate on each side of the tubular inverted-T-shaped coupling-lug *b*, it being bridged or partly closed between its right and left portions by said coupling-lug. In this slot the latch *C* is placed so that its upper edge comes flush 50 with the top of the plate *B'* and its legs *c'* pass entirely through the slot *d* and enter snugly into the reduced ends of the slot *a'* of the iron proper.

The curved wooden portion *B*, forming the handle proper, is provided at its base ends, 55 on the inner surface, with vertical slots *f* for the reception of the extremities *f'* of the spring-actuated latch, said slots *f* serving in conjunction with the slot in the plate as guides, while the shoulders at their upper 60 ends limit the upward movement of the latch, and thus while the latch is guided by the slot of the plate and the latching-legs, it is kept from being lifted to a height which would bring the ends of the legs above the 65 plate and allow the latch to move to one side or get out of connection with the handle, which sidewise movement would take place

if the extremities of the latch were not inserted into the slots *f* and the legs of the latch were lifted above the top of the plate. Of course the latch would be guided without the slots *f*, and therefore these slots are only specially useful for holding the latch in its connected relation to the handle under all circumstances. 75

A flat spring *C'* is interposed between the knob *C'* and the latch *C*, the outer ends of the said spring resting in recesses *C* and being secured between the plate *B'* and the lower edges of the wooden handle and secured centrally of its ends to the latch *C* by means of the knob *C'*, so as to bear upon the top of the latch and hold the same normally down. By this construction the latch is not only rendered automatic in its locking action, 85 but said action is rendered very quick, positive, and certain. This is regarded as a very important feature of the invention.

When it is desired to attach the handle to the heated iron proper, the lug *b* is placed by the handle lengthwise of the passage leading into the chamber *a*, the handle lowered, the lug forced into said passage, and during this operation the latch is forced up by the legs coming in contact with the top of the iron proper. Now 90 by giving a quarter-turn to the handle the lips *b'* of said lug will be forced under the overhanging flanges formed by the top plate of the iron, so that the handle will be held against separation by an upward pull upon 95 it from the iron proper. At the instant that the handle is turned to the above-mentioned position the latch, by reason of the spring, immediately descends and its legs enter the reduced ends of the slot *a'* of the iron proper 100 and effectually prevent the handle from being turned back until said legs are raised by the button or knob and are disengaged from the walls of said slots.

To cast the plate *B'* with the inverted-T-headed coupling on its under side and also with the passages *d'* in the widened central part of the plate, the sand to form the passages is molded up through holes in the pattern. 115

The lifting-button *C'* is attached to a pin secured to the latch central of its length, and thus can be conveniently manipulated and caused to draw both of the legs of the latch at the same instant out of the slot *a'*, and thereby unlatch the handle and allow it to be turned at a right angle to the coupling-passage and to be uncoupled from the iron proper. 120

Having now described my invention, what 125 I claim is—

1. In a sad-iron, the combination of a body portion provided with a central socket having overhanging flanges, a detachable handle having a plate attached to its lower ends, the 130 said plate being constructed with a downwardly, transversely arranged and an inverted-T-headed coupling-lug and with a vertical, elongated opening for the passage of

a spring-actuated latch or bar having a knob located about midway of its length for lifting the same so as to be readily grasped between the fingers without removing the hand from the handle of the iron, a flat spring for actuating the latch or bar extending the entire length of the same, and secured about midway of its length to the top of the latch by the lifting-knob, the outer ends of the spring being secured between the lower ends of the handhold and the handle-plate, the construction and arrangement being such, that when the handle is properly placed on the body of the iron proper, at right angles thereto, the inverted-T-headed coupling-lug will enter the passage, and when the handle is turned parallel with the longitudinal axis of the body of the iron proper the inverted-T head will pass beneath the overhanging flanges of the body portion proper and the spring-actuated latch will automatically descend and prevent the handle from being turned, substantially as described.

2. In a sad-iron the combination of a body portion provided with a central chamber, and

a removable cover forming overhanging flanges, said cover being provided with an elongated slot having an enlarged central portion, and a centering-pin arranged within the enlarged portion of said slot of the removable cover and projecting vertically from the interior of the iron proper, a detachable handle having a plate attached to its lower ends, said plate being connected with a downwardly-extending transversely-arranged and inverted-T-headed coupling-lug; an automatically-operating engaging latch operating in a slot in the base of the handle and provided with a knob for lifting the same, and with engaging lugs, and a flat spring resting upon the top of the latch and connected therewith between its ends by means of the lifting-knob, the outer ends of said spring being secured to the handle, substantially as described.

In testimony whereof I hereunto affix my signature in presence of two witnesses.

PETER C. GREENAWALT.
